United States Patent Office.

N. BANGS WILLIAMS, OF NEW YORK, N. Y.

Design No. 3,741, dated November 2, 1869.

DESIGN FOR A TRUNK-COVER.

The Schedule referred to in these Letters Patent and making part of the same.

I, N. BANGS WILLIAMS, of the city, county, and State of New York, have invented and produced a new and original Design for Covering Trunks.

The accompanying drawing, referred to herein, is a correct representation of my design.

Figure 1 represents that portion which covers the lid of the trunk upon its top, and the sides thereof.

Figure 2 shows that portion of the design to be used for the ends of the trunk, both for the lid and body of the same.

a a, in this figure, represent escutcheons, and are used to mark the place where the handle is fastened.

Figure 3 shows that part of the design to be used in covering the front of the trunk, the space above the ornamental figure is that occupied by the lock.

The special features of my design are, enclosing each separate portion thereof within a border consisting of one broad or heavy and two narrow lines, and subdividing the space into compartments by means of single

broad lines springing from the inner narrow line of the border, and also the ornaments shown respectively in figs. 1, 2, and 3.

I do not claim the dividing of a trunk into panelled compartments by means of lines, nor by the use of one broad and one narrow line, as this has been done before; but

What I do claim, is—

Enclosing the covering of a trunk within a border of three lines, one broad and two narrow, and subdividing the same into compartments by single broad lines springing from the inner narrow line of the border, and also the ornamental figures in the different compartments, as shown in the three figures of the drawing.

N. BANGS WILLIAMS.
